COMPUTER KEYBOARD

Bradley A. Beals, Bloomington, Raymond J. Gormley,
Prior Lake, and Jay Sucre, Newport, Minn., assignors
to Sperry Rand Corporation, New York, N.Y., a cor-
poration of Delaware

Original design application Apr. 26, 1961, Ser. No. 64,906.
Divided and this application May 15, 1963, Ser. No.
74,898

Term of patent 14 years

(Cl. D26—5)

Fig. 1

Fig. 3

Fig. 4

Fig. 2

FIGURE 1 is a perspective view of a computer key-
board showing our new design;

FIGURE 2 is a side elevational view thereof;

FIGURE 3 is a top plan view; and

FIGURE 4 is a back view.

The dominant features of our design reside in the por-
tion shown in full lines. This application is a division
of our copending application Serial No. D. 64,906, filed
April 26, 1961.

We claim:

The ornamental design for a computer keyboard, sub-
stantially as shown and described.
